DESIGN FOR A HAND TRUCK

Theodore L. Kuhns, Salem, Oreg.

Application May 20, 1939, Serial No. 85,106

Term of patent 14 years

To all whom it may concern:

Be it known that I, Theodore L. Kuhns, a citizen of the United States, residing at Salem, in the county of Marion and State of Oregon, have invented a new, original, and ornamental Design for a Hand Truck, of which the following is a specification, reference being had to the accompanying drawing, forming part thereof.

I claim:

The ornamental design for a hand truck, as shown.

THEODORE L. KUHNS.
